(57) **CLAIM**

The ornamental design for a cleaning device component, as shown and described.

DESCRIPTION

FIG. 1 is a perspective view of a cleaning device component showing my new design.

FIG. 2 is a front elevation view thereof the rear view being a mirror image;

FIG. 3 is a left side elevation view thereof the right side being a mirror image;

FIG. 4 is a top plan view thereof;

FIG. 5 is a bottom plan view thereof;

FIG. 6 is a bottom perspective view of the cleaning device component of FIG. 1;

FIG. 7 is an enlarged view of the portion labeled "7" encircled in FIG. 1; and,

FIG. 8 is an enlarged view of the portion labeled "8" encircled in FIG. 6.

The cleaning device component is shown with a symbolic break in its length. The appearance of any portion of the article between the break lines forms no part of the claimed design.
